The ornamental design for a hand truck, as shown and described.

DESCRIPTION

FIG. 1 is a perspective view of a hand truck in a use position showing my new design;

FIG. 2 is a top plan view thereof;

FIG. 3 is a bottom plan view thereof;

FIG. 4 is a right elevation view thereof; the left elevation view being a mirror image thereof;

FIG. 5 is a front elevation view thereof;

FIG. 6 is a rear elevation view thereof;

FIG. 7 is a perspective view of the hand truck of FIG. 1 in a collapsed storage position showing my new design;

FIG. 8 is a top plan view thereof;

FIG. 9 is a bottom plan view thereof;

FIG. 10 is a right elevation view thereof; the left elevation view being a mirror image thereof;

FIG. 11 is a front elevation view thereof; and,

FIG. 12 is a rear elevation view thereof.

The broken lines in the drawings are included for the purpose of illustrating elements of the hand truck and form no part of the claimed design.
